UNITED STATES PATENT OFFICE.

ROBERT L. WALKER, OF BOSTON, MASSACHUSETTS, ASSIGNOR TO THE
WALKER SMOKELESS FURNACE COMPANY, OF SAME PLACE.

DAMPER.

SPECIFICATION forming part of Letters Patent No. 293,543, dated February 12, 1884.

Application filed May 23, 1883. (No model.)

To all whom it may concern:

Be it known that I, ROBERT L. WALKER, of Boston, in the county of Suffolk and State of Massachusetts, have invented a new and useful
5 Improvement in Dampers, of which the following is a specification.

My invention relates to improvements in dampers used to close the outlets of furnaces, more especially of steam-boiler furnaces, in
10 which two separate fires are placed—one at each end of the boiler—and by means of dampers the smoke and gases generated in one fire are made to pass over the other fire. My object is to keep the damper from leaking around
15 the edges, when it is in place, even when it may become warped by the heat.

My invention consists in providing the damper with a beveled flange on one side and a concavity on the other side for holding a refractory sand, and providing the lower damper-seat with a concavity for holding a refractory sand, and the upper damper-seat with a beveled flange similar to that on the damper, so that these beveled flanges will penetrate this
25 sand to a greater or less depth, according to the bends or warps, and thereby prevent any leakage of gases between the damper and its seats.

In the accompanying drawings, which illustrate a steam-boiler with two fires and my improved damper, Figure 1 is a side elevation, partly in section. Fig. 2 is a longitudinal section, and Fig. 3 is a cross-section through the damper and its seat.

35 The boiler A is provided with furnaces B B'—one at each end—provided with outlets b b'. These outlets b b' are covered alternately by the dampers D D', the smoke from the covered furnace being caused to pass over the fire in
40 the uncovered furnace through its outlet and back through the tubes of the boiler A to one of the flues E E', and thence to the chimney.

These flues E E' must be covered by a damper when the outlet of its furnace is uncovered. Heretofore the dampers have been made flat, 45 and have rested on flat seats around the outlets and flues; and it has been found that the intense heat warps the dampers more or less, so that they do not fit close to their seats, but allow the smoke and gases from the fresh fuel 50 in the covered furnace to escape unconsumed between them and their seats. With my improved dampers a joint sufficiently tight to prevent any injurious leakage is simply and effectually provided. On the lower side of the 55 dampers, I make a beveled flange or projection, d d', and on the upper side a trough or groove, d' d''. A similar trough is formed around each of the outlets b b', and a similar flange around the flues E E'. The troughs are filled to the 60 required depth with a refractory sand, or the like, into which the projections on the lower side of the dampers and the lower side of the flues enter, when the damper is in position to cover these outlets or flues. The sand forms 65 a perfect packing to prevent the escape of smoke or gas between the dampers and their seats. The smoke and gases are therefore compelled to pass over the fire in the uncovered furnace, which, by proper firing, is kept incandescent, and are consumed, thereby preventing 70 smoke and economizing fuel.

I claim as my invention—

In a damper for covering openings above and below it, a pointed projection on one side and 75 a trough on the other side, adapted to enter a trough in the lower seat and to receive a pointed projection on the upper seat, substantially as and for the purposes set forth.

ROBERT L. WALKER.
